ATTORNEYS

UNITED STATES PATENT OFFICE.

JAMES G. SMITH, OF ALLIANCE, OHIO.

CALENDAR-INKSTAND.

SPECIFICATION forming part of Letters Patent No. 239,867, dated April 5, 1881.

Application filed January 22, 1881. (No model.)

To all whom it may concern:

Be it known that I, JAMES G. SMITH, a citizen of the United States, resident at Alliance, in the county of Stark and State of Ohio, have 5 invented certain new and useful Improvements in Calendar-Inkstands; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification, and in which—

15 Figure 1 is a cross-section. Fig. 2 is a top view. Fig. 3 is a side view.

This invention relates to calendar-inkstands; and it consists in the construction hereinafter described, and particularly pointed out in the 20 claim.

In the drawings hereto annexed, A is an inkstand, having the ink-chamber B and nose C. It is made without any casing, and, except in the particulars hereinafter mentioned, of 25 any material. Around the nose C is sprung a band of rubber or spring metal, Z, having on its outer surface the days of the week, arranged in order as shown, said band being loose enough to turn. The top of the ink- 30 stand is divided into five concentric rings and seven sectors by the lines, as shown. The numbers of the days in the months, from one to thirty-one, are arranged in order in the spaces, as shown in the drawings. Extending around this top is the rim D, having the notches d, forming pen-racks. The bottom of the ink- 35 stand extends below in a rim, E, which is beveled off inwardly, as shown at e. Sprung into this bevel is a band, F, containing on the out-

side the names of the months, duly spaced, 40 and having on its inner face a button, f, for turning. The rim E is opaque except at one point, z, where the proper month is to be exposed.

In use the proper day of the week is turned 45 to the first of the month, when the others will properly follow, and the proper name of the month is turned to the transparent or open point z.

A calendar-inkstand having formed upon 50 its surface the numerals representing the days of the month and the names of the days of the week, constructed so that the names of the days of the week can be adjusted in proper relation to the date of the month, no month, 55 however, being designated, is not new. Calendar-rings encircling the stand within a receptacle are also old. I desire protection only for what is hereinafter specifically claimed.

An inkstand having on its surface the names 60 of the months, numerals representing the days of the month and the names of the days of the week on an adjustable band, is not new; and protection is only sought for the construction hereinafter specifically claimed. 65

What I claim is—

In a calendar-inkstand, the opaque lower rim, E, having opening z, and beveled off inwardly, in combination with band F, having the names of the months in its outer surface, 70 and sprung into the bevel of said rim, substantially as described.

In testimony whereof I affix my signature in presence of two witnesses.

JAMES G. SMITH.
